UNITED STATES PATENT OFFICE.

FRANK EARL TOUCHY, OF GALVESTON, TEXAS.

SPEED-OPERATED CIRCUIT-CLOSER.

1,346,067.

Specification of Letters Patent.

Patented July 6, 1920.

Application filed July 3, 1919. Serial No. 308,398.

To all whom it may concern:

Be it known that I, FRANK EARL TOUCHY, a citizen of the United States, and a resident of Galveston, in the county of Galveston and State of Texas, have invented a new and Improved Speed-Operated Circuit-Closer, of which the following is a description.

My invention has reference to circuit closers and more particularly is intended for use in connection with an alarm on elevators for grain and other foodstuffs in which the belt not infrequently slips or the elevator chokes owing to too much feed, loose buckets, or 15 some obstruction in the head or boot of the elevator, causing the loss of time and sometimes producing very serious fires.

I have in view to provide a circuit closer in connection with an alarm and controlled 20 by a governor driven by the elevator belt, so that when the belt slips or stops from being choked or obstructed the governor will act through the circuit closer to cause an alarm to be sounded.

25 A more specific object of the invention is to provide a circuit closer of the indicated character that may be applied to a wall of any elevator.

Reference is to be had to the accompanying drawings forming a part of this specification, it being understood that the drawings are merely illustrative of one example 30 of the invention.

Figure 1 is a side elevation showing my 35 invention applied to an elevator illustrated in part;

Fig. 2 is a partly sectional plan view;

Fig. 3 is a partly sectional side elevation.

40 The letter A indicates conventionally a portion of an elevator and B wall thereof adjacent to which the elevator belt C travels.

In carrying out my invention in accordance with the illustrated example, a casing 45 10 is provided having means to be secured in position on the wall B, there being shown provided in the present instance a flange 11 on the casing, secured by suitable fasteners 12 to the wall B. The casing is equipped 50 with suitable bearings 10^a for a shaft 13 on which is a drive wheel or pulley 14 that projects beyond the open side of the casing and beyond the wall B sufficiently to be frictionally engaged by the elevator belt C and 55 driven thereby. On the shaft 13 are the governing means controlling the alarm as

follows: The hub 15 of the governor is secured to shaft 13 by a set screw 15^a or equivalent means and projecting radially beyond said hub are arms 16 preferably in 60 the form of stud bolts screwing into hub 15. On said arms are loosely mounted rollers 17, the bolts having nuts 18 outside of said rollers. The arrangement is such that when the device is being driven by the belt 65 C centrifugal force will maintain rollers 17 in their outer positions but upon the stopping or slipping of the belt and the stopping of the drive wheel 14 or a material slowing down thereof, a roller 17 as it approaches the 70 top position will gravitationally descend on the arm 16 to position indicated in dotted lines and will serve to sound an alarm. In the preferred embodiment of my invention 75 an electrical alarm is provided in the circuit of which is an arcuate resilient contact 19 suitably secured as at 20 at one end to the casing 10, and lying in the path of movement of the rollers when in the inward position so that pressure of the roller in passing over contact 19 will flex the same into engagement with the fixed contact 19^a and close the electric circuit. From the circuit closer the conductor wires 21 run to a suitable signal 22, here shown as a known form 80 of bell and there being included in the circuit any approved switch 23.

I would state in conclusion that while the illustrated example constitutes a practical embodiment of my invention, I do not limit 90 myself strictly to the mechanical details herein illustrated, since manifestly the same can be considerably varied without departure from the spirit of the invention as defined in the appended claims.

Having thus described my invention, I claim as new, and desire to secure by Letters Patent:

1. An attachment of the class described including a shaft, a friction pulley on said shaft, and adapted to be driven by engagement of a belt, radial arms on said shaft, rollers loose on said arms to be maintained in an outer position under centrifugal force and adapted to gravitationally assume an inner position when an arm is at the top of the shaft and in the absence of centrifugal action, and a circuit closer controlled by a roller when in the inner position.

2. A circuit closer of the class described including a casing having means to secure the same in position, a shaft turning in said

casing, a drive pulley on said shaft adapted to be driven by a belt when the device is in position, radial arms on said shaft, rollers loose on said arms to move radially thereon 5 to an outer position under centrifugal force or to gravitate radially inward when an arm is at the top of the shaft and in the absence

of centrifugal force, and fixed contacts mounted on the casing and including a resilient contact adjacent to the path of travel 10 of the rollers when in the inner position and curved in an arc struck approximately from the center of the shaft.

FRANK EARL TOUCHY.
